MOBILE SERVER FOR ICE CREAM CABINETS

Roy Emanuele, 204 Bel Air Drive,
Massapequa, N.Y. 11758

Filed Jan. 7, 1972, Ser. No. 216,323

Term of patent 14 years

Int. Cl. D12—02

U.S. Cl. D12—22

FIG. 1

FIG. 2

FIG. 1 is a perspective view of a mobile server for ice cream cabinets showing my new design;

FIG. 2 is a front elevational view thereof;

FIG. 3 is a rear elevational view thereof;

FIG. 4 is a top plan view thereof; and

FIG. 5 is a left side elevational view thereof.

I claim:

The ornamental design for a mobile server for ice cream cabinets, substantially as shown.
